CLAIM

The ornamental design for a furniture support leg or similar article, as shown and described.

DESCRIPTION

FIG. 1 is a perspective view of a furniture support leg or similar article showing my new design;

FIG. 2 is a left side elevational view;

FIG. 3 is a front elevational view;

FIG. 4 is a top plan view; and,

FIG. 5 is a bottom plan view thereof;

FIG. 6 is a perspective view of a furniture support leg or similar article, showing a second embodiment of my design;

FIG. 7 is an elevational view;

FIG. 8 is a top plan view; and

FIG. 9 is a bottom plan view thereof.
